Inventor:
George G. Wehr,
By Leonard L. Kalish
Attorney.

UNITED STATES PATENT OFFICE

GEORGE G. WEHR, OF PHILADELPHIA, PENNSYLVANIA

DIKE CONSTRUCTION

Application filed December 18, 1929. Serial No. 415,055.

My invention relates to a new and useful dike construction or break-water adapted particularly for reclaiming lowland or partly submerged land.

5 My invention further relates to a novel construction in dikes or break-waters or the like, whereby the same may be laid or constructed submerged in water with great facility and ease and at minimum cost, and 10 whereby durable and efficient breakwater or seawall is produced.

With the above ends in view, my invention consists in permanently and securely interlocking and interconnecting a series of ship-hulls end to end, to form a firm and durable wall.

My invention further consists in recessing the stern overhang of each ship-hull, sufficiently to permit the bow of the adjacent 20 ship-hull to be abutted against the stern post of the ship-hull, thereby forming a tongue and groove connection between adjacent ship-hulls, and then fastening the stern of one ship hull to the bow of the other ship-hull 25 by means of suitable planking.

My invention further consists of other novel details of construction to be described more in detail hereinafter.

For the purpose of illustrating my invention I have shown in the accompanying drawing one form thereof which is at present preferred by me, since the same has been found in practice to give satisfactory and reliable results, although it is to be understood 35 that the various instrumentalities of which my invention consists can be variously arranged and organized and that my invention is not limited to the precise arrangement and organization of the instrumentalities as herein shown and described.

40 Referring to the drawing in which like reference characters indicate like parts,

Figure 1 represents a vertical sectional view of land which is to be reclaimed and the 45 relation of the dike or break-water thereto of my novel construction.

Figure 2 represents a top plan view of the same.

50 Figure 3 represents a side elevation of the bow of one ship-hull and the stern of the ad-

jacent ship-hull united into a dike of my novel construction.

Figure 4 represents a top plan view of the same.

The object as stated herein above, is to reclaim land by means of a sea-wall, dike or break-water, or to form such sea-wall, dike or break-water for any other purpose for which the same may be utilized. In the particular illustration shown in Figures 1 and 2 the dike is built for the reclamation of land.

Old ship-hulls, preferably wooden ship-hulls 5, are cut away at the stern overhang 6 thereof, by cutting a generally V-shaped notch into said stern overhang up to the stern post 7.

The ship-hull is then loaded with any suitable material, such as rocks or refuse and floated into position. The thus loaded and positioned ship-hull is then sunk into position 70 by opening the sea-gate or the like and admitting water thereinto. The next ship-hull, similarly cut away at the stern overhang, is similarly loaded and floated in position 75 with the bow in alignment with the stern overhang of the previously lowered ship-hull. It is then sunk in position in line with the previously lowered hull in such a way that the bow 8 enters the V-shaped notch 9 cut into the stern overhang of the previously lowered ship-hull. Planks 10 are then secured to the adjacent bow and stern portions as indicated in Figures 3 and 4 by suitable spikes or the like. The planking 10 may be extended clear to the bottom so as to close the opening between adjacent ship-hulls.

By this means a continuous line or chain of ship-hulls may be firmly united, with adjacent ship-hulls interlocked with each other in tongue and groove fashion and also united 90 with each other by permanent fastenings such as the planks 10. The line or chain of ship-hulls shown particularly in Figure 2, then forms a wall which may form the basis of 95 the reclamation of the land within the wall or which may serve any other purpose desired.

In the practice of my invention I may employ old dismantled ship-hulls. The ship- 100

hulls may be loaded with any suitable material available at the particular time.

I am aware that my invention may be embodied in other specific forms without departing from the spirit or essential attributes thereof and I therefore desire the present embodiment to be considered in all respects as illustrative and not restrictive, reference being had to the appended claims rather than to the foregoing description to indicate the scope of the invention.

Having thus described my invention, what I claim as new and desire to secure by Letters Patent, is:

1. The method of building dikes, which consists in cutting a notch in the stern overhang of ship-hulls, placing a series of said notched ship-hulls end to end in line formation to form a dike, with the bow of each successive ship-hull inserted into the notch in the stern overhang of the adjacent ship-hull, thereby to form a tongue and groove-like connection between adjacent ship-hulls.

2. The method of building dikes, which consists in cutting a notch in the stern overhang of ship-hulls, placing a series of said notched ship-hulls end to end in line formation to form a dike, with the bow of each successive ship-hull inserted into the notch in the stern overhang of the adjacent ship-hull, thereby to form a tongue and groove-like connection between adjacent ship-hulls, and securing planking or the like across the adjacent ends of the ship-hulls to close the clearance space therebetween.

3. The method of building dikes, which consists in cutting a notch in the stern overhang of a series of ship-hulls, loading said ship-hulls with any suitable ballast, sinking said series of ship-hulls in position one after the other, and in the desired alignment with each other, with the bow of each ship-hull positioned and fitted within the notch in the stern overhang of the previously lowered ship-hull.

4. The method of building dikes, which consists in cutting a notch in the stern overhang of a series of ship-hulls, loading said ship-hulls with any suitable ballast, sinking said series of ship-hulls in position one after the other, and in the desired alignment with each other, with the bow of each ship-hull positioned and fitted within the notch in the stern overhang of the previously lowered ship-hull, and lastly securing planking across the adjacent ends of the successive ship-hulls permanently to unite the same.

5. A dike, break-water or sea-wall or the like, consisting of a line of ship-hulls positioned end to end and suitably ballasted, the stern overhang of each ship-hull being notched and the bow of each ship-hull being positioned in the notch of the adjacent ship-hull in tongue and groove fashion.

6. A dike, break-water or sea-wall or the

like, consisting of a line of ship-hulls positioned end to end and suitably ballasted, the stern overhang of each ship-hull being notched and the bow of each ship-hull being positioned in the notch of the adjacent ship-hull in tongue and groove fashion, and planking secured across the adjacent ends of the line of ship-hulls to enclose the clearance space therebetween and permanently to unite the same.

In testimony whereof, I have hereunto set my hand.

GEO. G. WEHR.
